A. E. BAILEY, JR

ELECTRIC SWITCH

Filed Dec. 10, 1926

Inventor:
Allen E. Bailey, Jr.
by Alvord S. Ladd
His Attorney.

UNITED STATES PATENT OFFICE.

ALLEN E. BAILEY, JR., OF SCHENECTADY, NEW YORK, ASSIGNOR TO GENERAL ELECTRIC COMPANY, A CORPORATION OF NEW YORK.

ELECTRIC SWITCH.

Application filed December 10, 1926. Serial No. 153,974.

My invention relates to electric switches, and has for its object the provision of a simple and reliable electric switch whereby one or more conductors can be electrically connected to any one of a plurality of conductors as desired.

More particularly my invention relates to switches for selectively establishing an electrical connection between a given point and any one of a plurality of points. In one of its aspects my invention relates to a rotary selector switch which operates to connect an incoming or outgoing line with any one of a plurality of circuits. My invention has general application in the control of electrical apparatus and has particular application to electric signaling systems, for example, in the operation of motion transmission systems in which it may be desired to connect any one of a plurality of motion receiving devices with a single motion transmitting device.

In carrying out my invention in one form, I provide a plurality of stationary contact members and a rotor provided with contact members arranged to cooperate with the stationary contact members in such manner that a predetermined stationary contact member can be connected to any one of the remaining stationary contact members as desired.

For a more complete understanding of my invention reference should be had to the accompanying drawing in which Fig. 1 is a side elevation view of an electric switch embodying my invention; Fig. 2 is a sectional view along the line 2—2 of Fig. 1 looking in the direction of the arrows; Fig. 3 is a sectional view along the line 3—3 of Fig. 2 looking in the direction of the arrows; Figs. 4 and 5 are enlarged views showing details of construction, Fig. 5 being a sectional view along the line 5—5 of Fig. 4 looking in the direction of the arrows; Figs. 6 to 13 inclusive are diagrammatic views showing the electrical connections for various positions of the switch while Fig. 14 is a front elevation view showing the knob and dial of the switch; Fig. 15 is a diagrammatic view of the connections in a modified form of my invention.

Referring to the drawing, I have shown my invention in one form in connection with a selector switch whereby a plurality of incoming or outgoing lines may be separately connected as desired with the conductors of any

one of several sets of outgoing or incoming lines. As shown in Fig. 1, the switch is provided with eight individual switching elements 10-17 inclusive, these elements being identical in construction and each element performing the switching functions whereby some one line wire may be connected with any one of a plurality of lines. With the arrangement shown, in which eight switching elements are provided as many as eight line wires can be taken care of, although obviously the capacity of the switch may be increased by increasing the number of switching elements.

As shown in Fig. 2 each switching element comprises a plurality of stationary contact members which, in the form shown, are secured in equally spaced positions on a supporting ring 18 made of suitable insulating material, such as fibre or a bakelite compound. As shown, nine of these contact members, numbered 20-28 inclusive are provided, although obviously any suitable number may be used depending upon the number of circuits to be controlled. Cooperating with the stationary contacts are a plurality of movable contacts 29 secured to a rotor member comprising a disk 30 made of a suitable electrically insulating material which is secured on a rotor shaft 31. The rotor disks 30 are secured against rotation by means of rods 31^a and 31^b on opposite sides of the shaft 31 and secured in parallel relation therewith by means of cross members 31^c and 31^d (Fig. 1) secured to the shaft 31. The rods 31^a and 31^b and the shaft 31 pass through apertures in the rotor disks, which are secured against displacement longitudinally of the rods and shaft by suitable spacing sleeves on the shaft 31. As previously noted an odd number of stationary contacts are provided but, on the other hand, an even number of rotor contacts 29 are used. These rotor contacts are attached to the disk 30 so as to project somewhat, as shown, from the periphery of the disk and thereby engage the stationary contacts as the disk is turned by means of the shaft 31. The spacing of the contacts 29, in this form of my invention, corresponds to the spacing of the stationary contacts, i. e., the angle included by lines joining two adjacent contacts 29 with the center of the shaft 31 is equal to the angle

included by similar lines passing through two adjacent stationary contacts. Since there is one less rotor contact, however, the space between one pair of rotor contacts is 5 double the spacing of the remaining contacts. This pair of contacts, separated by the double spacing, are electrically connected together by a bridging conductor 32 and the remaining rotor contacts are electrically connected 10 together in a similar manner by means of bridging conductors 33, 34 and 35, oppositely disposed contacts lying in planes parallel to the plane of the first pair of contacts being connected together as shown in the 15 drawing.

In order to improve the electrical connections between the stationary and rotating contacts a contact shoe or member 36 is pivoted on the inner end of each stationary contact 20 member. As shown in Figs. 4 and 5 the inner ends of the stationary contact members are forked, the shoe 36 being mounted between the two projections thus formed on a pivot pin 37. One end of the contact shoe which is 25 provided with a contact surface is biased inward toward the rotor by means of a helical spring 38 which encircles the pivot pin 37. The opposite end of the shoe engages the body of the stationary contact member at point 39 30 so as to limit the inward movement of the contact shoe. The contact shoes are so situated with respect to the rotor contacts 29 that each shoe will be moved outward slightly about its pivot as a rotor contact passes beneath it 35 whereby a good electrical contact is assured.

In the operation of the switch the stationary contact members will be electrically connected to the lines to be controlled. As shown these stationary contact members are provided 40 with screws 40 whereby these electrical connections can be made. Some one of the stationary contacts will be connected to the line wire which it is desired to connect with a plurality of wires. In the arrangement 45 shown, it has been assumed that the contact member 20 will be connected to this line. The remaining contact members 21-28 inclusive will be connected respectively to the line wires with which connection is to be made. With 50 the switch connected in this manner the rotor is in off position when turned to the position shown in Fig. 2, since in this position the stationary contact member 20 lies in the gap between the double spaced rotor contacts and is not connected with any one of the 55 other stationary contacts. In order to facilitate the operation of the switch, the rotor 31, which may be turned by means of a knob 41, is provided with a pointer 42 cooperating with 60 a scale plate 43 on which are indicated the off positions and eight operating positions, numbered 1-8 inclusive, as shown in Fig. 14. The electrical connections for the various positions of the rotor are indicated in Figs. 6 to 65 13 inclusive which correspond with positions

1-8 inclusive respectively. It will be noted that when the rotor is turned in a clockwise direction as observed in Fig. 14, i. e. counterclockwise as observed in Figs. 2 and 6 to 13 inclusive, connections are successively established between the contact member 20 and the remaining contacts in positions 1 to 8 inclusive in the following order respectively: 22-24-26-28-21-23-25-27. It will be observed that a complete revolution of the rotor is required in making the connections and consequently if desired the rotor may be turned in either direction to the proper position. For example, the rotor may be turned in a counterclockwise direction from 80 position 1 as indicated in Fig. 6 to position 8 as indicated in Fig. 13 or the rotor may be turned to off position in either direction.

In the arrangement shown in Fig. 1 the insulating supporting rings 18 of the various switching elements are mounted on parallel rods 44 in spaced relation to each other and the disks 30 of the rotor members are secured to the shaft 31 in correspondingly spaced positions. Brackets 45 and 46 are provided at 85 the ends of the rods 44 in which the rotor shaft 31 is rotatably mounted. As shown the switch is mounted on a suitable panel board 47 the bracket 45 being secured to the panel board by means of screws 48 and 49. The shaft 31 extends through the panel and the knob and pointer are on the opposite side from the switching elements.

Obviously as previously indicated any suitable number of switching elements may be 100 operated from a single rotor shaft to accommodate the number of circuits to be controlled. Furthermore, the number of circuits controlled by each switching element can be varied as desired by varying the number of stationary and rotating contacts. It is preferable, however, to provide an odd number of stationary contacts and an even number of rotating contacts.

In the modified form of my invention, 110 shown diagrammatically in Fig. 15, the stationary contacts are spaced unequally around the rotor. As shown, there are five stationary contacts 50 to 54 inclusive, whereby only two short circuiting conductors or members 115 55 and 56 are provided on the rotor 57. The contact 50 is the line contact which is to be connected to any one of the contacts 51 to 54 inclusive. Although various arrangements of the contacts may be used, in the particular 120 arrangement shown the contacts 51 to 54 inclusive are equally spaced about the rotor, the contact 50 being located midway between the contacts 51 and 54. The bridging member 55 is of such length that it will connect 125 the contact 50 with the contact 52 in one position of the rotor, and will connect the contact 50 with the contact 53 in another position of the rotor, as will be understood from the previous description in connection with 130

the form shown in Figs. 1-14 inclusive. The bridging member 56, which is parallel with the member 55, is much shorter, however, and is of such length that it will connect the contact 50 with either the contact 54 or the contact 51 when the rotor is turned to the required positions to establish these connections.

The particular form of my invention shown in Fig. 15 has the advantage that when the rotor is in the off position, as shown in Fig. 15, the bridging contact members do not engage the stationary contacts, as is the case with the form of my invention shown in Figs. 1-14 inclusive. This avoids the possibility of any undesirable circuits being established when the rotor is in off position. Furthermore when the rotor is turned to any operating position to connect the contact 50 with any one of the contacts 51 to 54 inclusive, the particular connection desired is the only one established. For example, when the rotor is turned so that the bridging member 55 connects the contact 50 with the contact 52 the bridging member 56 does not at the same time rest on certain other contacts and electrically connect them together, as occurs in the form shown in Figs. 1-14 inclusive. Obviously, with this form of my invention any suitable number of stationary contacts can be used, a corresponding number of bridging members being at the same time provided.

While I have described my invention as embodied in concrete form and as operating in a specific manner in accordance with the provisions of the patent statutes, it should be understood that I do not limit my invention thereto since various modifications thereof will suggest themselves to those skilled in the art without departing from the spirit of my invention the scope of which is set forth in the annexed claims.

What I claim as new and desire to secure by Letters Patent of the United States, is:

1. A switch comprising a plurality of contacts, a plurality of bridging members of different lengths, and means for moving said members successively into engagement with one of said contacts so as to connect said contact selectively to each of the remaining contacts.

2. A switch comprising a plurality of stationary contacts, a rotor member, and a plurality of bridging conductors mounted on said rotor arranged to electrically connect a predetermined stationary contact with any one of the remaining stationary contacts when the rotor is turned.

3. A switch comprising a plurality of stationary contacts, a rotor member, and means carried by said rotor member for selectively connecting one of said stationary contacts to each of the remaining stationary contacts as the rotor is turned.

4. A selector switch comprising a plurality of stationary contacts spaced in a circle, a rotor, a plurality of bridging conductors on the rotor arranged to cooperate successively with a predetermined stationary contact as the rotor is turned and electrically connect said stationary contact to each one of the remaining stationary contacts.

5. A selector switch comprising a plurality of stationary contacts, a rotor member and a plurality of bridging members on said rotor cooperating with one of said stationary contacts successively as the rotor is turned to connect said stationary contact to the remaining stationary contacts in alternate order, said stationary contact being connected to each of the other contacts once each revolution of said rotor and said bridging members being used twice each revolution of said rotor.

6. A selector switch comprising a plurality of stationary contacts equally spaced in a circle, a rotor, and a plurality of bridging members on said rotor of varying length arranged to connect one of said stationary contacts to each of the remaining stationary contacts as said rotor is turned.

7. A selector switch comprising a plurality of stationary contacts, a rotor, and a plurality of bridging members on said rotor arranged to be moved successively into engagement with one of said stationary contacts as the rotor is turned to connect said stationary contact to each of the remaining contacts in alternate order each revolution of said rotor.

8. A selector switch comprising an odd number of stationary contacts, a rotor, an even number of contacts on said rotor spaced to correspond with the spacing of said stationary contacts, and electrical connections between oppositely disposed contacts on said rotor whereby a predetermined stationary contact is connected to each of the remaining stationary contacts as the rotor is turned.

9. A selector switch comprising an odd number of stationary contacts, a rotor, an even number of contacts on said rotor spaced to engage a corresponding number of said stationary contacts simultaneously, one pair of said rotor contacts having a double spacing, a conductor connecting said pair of contacts, and conductors connecting the remaining rotor contacts together in pairs, oppositely disposed rotor contacts being connected together.

10. A switch comprising a plurality of unequally spaced contacts, a plurality of bridging members of different lengths, and means for moving said members successively into engagement with one of said contacts so as to connect said contact selectively to each of the remaining contacts.

11. A selector switch comprising a plurality of stationary contacts unequally spaced in a circle, a rotor, and a plurality of bridging members on said rotor of varying length arranged to connect one of said stationary contacts to each of the remaining stationary contacts.

tacts to each of the remaining stationary contacts as said rotor is turned.

12. A selector switch comprising an odd number of stationary contacts equally spaced in a circle, a rotor, a plurality of bridging members of graduated lengths on said rotor, each of said bridging members being of such

length as to connect any predetermined one of said stationary contacts to one or the other of two of the remaining stationary contacts as to the rotor is turned.

In witness whereof, I have hereunto set my hand this 7th day of December 1926.

ALLEN E. BAILEY, JR.

CERTIFICATE OF CORRECTION.

Patent No. 1,701,352.

Granted February 5, 1929, to

ALLEN E. BAILEY, JR.

It is hereby certified that error appears in the printed specification of the above numbered patent requiring correction as follows: Page 4, line 11, claim 12, strike out the word "to"; and that the said Letters Patent should be read with this correction therein that the same may conform to the record of the case in the Patent Office.

Signed and sealed this 5th day of March, A. D. 1929.
